UNITED STATES PATENT OFFICE.

JAMES M. ALLEN, OF ST. LOUIS, MISSOURI, ASSIGNOR OF ONE-HALF TO GEORGE MERTENS, OF ST. LOUIS, MISSOURI.

ELECTRICAL APPARATUS FOR PRODUCING AND COLLECTING GASES.

Application filed February 27, 1922. Serial No. 539,389.

To all whom it may concern:

Be it known that I, JAMES M. ALLEN, a citizen of the United States, and resident of the city of St. Louis and State of Missouri, have invented certain new and useful Improvements in Electrical Apparatus for Production and Collecting Gases, of which the following is a specification, containing a full, clear, and exact description, reference being had to the accompanying drawings, forming a part hereof.

My invention relates to improvements in electrical apparatus for producing and collecting gases, and has for its primary object a device which is equipped with electrodes and hoods for breaking up and collecting gases from liquids by electrolysis.

A further object is to construct a device for producing gases by electrolysis and collecting the same in hoods located over the electrodes. The hoods being so arranged that the gases may be conducted wherever desired.

In the drawings,

25 Fig. 1 is a top plan view of my device.

Fig. 2 a vertical cross section taken on the line 2—2 of Fig. 1.

Fig. 3 a vertical longitudinal section taken on the line 3—3 of Fig. 2.

30 Fig. 4 a vertical cross section of one of the nozzles made use of when it is desired to pipe the gases.

In the construction of my device I employ a jar 6 which is open at its top. Its bottom 7 being provided with upwardly projecting ribs 8, which ribs serve as a support for the electrodes. The electrodes are preferably composed of a plurality of grids 9, which grids are secured in a crow's foot 10. This crow's foot being equipped with a binding post 11. The binding post is provided with an opening 11 into which an electric conductor is adapted to be inserted and secured therein by means of a screw 13. Surrounding the upper portion of each of the electrodes is a hood 14, which is provided with hooks 15. These hooks are adapted to hook over the upper edge of the jar 6 and support the hoods. The hoods 16 are held together along their inner faces by means of rivets or similar fastening means 17. These rivets are surrounded by sleeves 18 so as to prevent the hoods from contacting with each other. The top of the hoods 19 are curved laterally and inclined upward

toward the center longitudinally where it terminates in a screw threaded cylindrical portion 18. This acts as an outlet for the gases which accumulates under the hoods. The upper portion of the outlet 18 is screw threaded as at 19 to receive the screw threaded portion 20 of the nozzle 21. This nozzle is provided with corrugations so as to receive a rubber hose. The hoods 14 are each equipped with an integral screw threaded projection 22 through which the binding post 11 extends, and over this screw threaded projection is secured a packing nut 23 which secures the packing 24 tightly around the binding post and prevents the escape of any gas. In practice my device is filled with liquid sufficiently to cover both the grids and also the crow's foot. It is essential, of course, in operating my device that a direct current be employed. Where the only current available is alternating, it is necessary to pass the current through a rectifier such as is used for charging storage batteries.

The operation of my device is as follows:

After the device has been assembled as shown in the drawings, a liquid is poured into the jar. In case this liquid is ordinary water, only oxygen and hydrogen will be given off during its operation. The wires 25 are attached to the positive and negative posts as indicated in Fig. 1, and the current turned on. In the event that oxygen only is desired, a nozzle is put on the negative hood and a hose attached thereto and the 30 hydrogen conveyed away, while the oxygen is allowed to escape into the room. This oxygen may be permitted to escape directly from the hood, or it may be medicated by passing it through a liquid, or it may be 35 dried by passing it through lime or other moisture absorbing material.

I may by using various chemicals produce various gasses. I may also without departing from the spirit of my invention 40 fill the grid with a paste similar to storage battery plates, or I may use solid plates for the electrodes.

While I have shown the jar and hoods constructed of glass, I do not desire to limit 45 myself to the materials out of which these parts are constructed as it is obvious that other materials may be used and the same purpose achieved.

The only important feature being that 50

neither the jar nor the hood is of a material which acts as an electric conductor.

My object in extending the hoods downward so as to embrace or encircle the upper portion of the electrodes, is to prevent any intermingling of the gases.

My device is especially useful in sick-rooms and in rooms where large gatherings of people congregate, as the air can be purified and supplied with free oxygen, or the air can be supplied with a disinfectant.

Having fully described my invention, what I claim is:

1. An electrical apparatus for producing and collecting gases, comprising a jar, electrodes located in said jar, a liquid in said jar, hoods suspended in said jar, said hoods extending over and surrounding the upper portion of said electrodes and extending into said liquid.

2. An electrical apparatus for producing and collecting gases, comprising a jar, a liquid located in said jar, electrodes composed of a plurality of grids located in said liquid, a hood extending over and surrounding the upper portion of each of said electrodes suspended in said jar, and extending into said liquid, and an outlet formed integral with each of said hoods.

3. An electrical apparatus for producing and collecting gases, comprising a jar, a

liquid in said jar, electrodes located in said jar, hoods suspended in said jar, said hoods extending over and surrounding the upper portion of said electrodes and extending into said liquid and serving as a support for said electrodes, and hooks for suspending said hoods within the jar.

4. An electrical apparatus for producing and collecting gases, comprising a jar, a liquid contained thereby, electrodes composed of a plurality of grids located in said jar, a hood extending over and surrounding the upper portion of each of said electrodes suspended in said jar and extending into said liquid said hoods also serving as a support for said electrodes, an outlet formed integral with each of said hoods.

5. An electrical apparatus for producing and collecting gases comprising a jar, a pair of hoods secured together in spaced apart position, a liquid in said jar, hooks secured to said hoods for suspending the same within the jar and liquid, electrodes carried by each hood and extending beyond the lower edge thereof, means carried by the hoods for securing the electrodes thereto and an outlet formed integral with the top of each hood.

In testimony whereof, I have signed my name to this specification.

JAMES M. ALLEN.
